(57) CLAIM

The ornamental design for a shoe outsole, as shown and described.

DESCRIPTION

FIG. 1 is a front perspective view of a shoe outsole showing our new design;

FIG. 2 is a bottom view thereof;

FIG. 3 is a rear perspective view thereof;

FIG. 4 is an enlarged view of the claimed region in FIG. 1, shown in isolation;

FIG. 5 is an enlarged view of the claimed region in FIG. 2, shown in isolation; and,

FIG. 6 is an enlarged view of the claimed region in FIG. 3, shown in isolation.

The broken line immediately surrounding the cluster of three-pronged grooves represents an unclaimed boundary of the design. The unshaded region between the three-pronged grooves and within the unclaimed boundary depicts unclaimed subject matter and forms no part of the claimed design. The broken lines showing the remainder of the shoe are for environmental purposes only and form no part of the claimed design.
